UNITED STATES PATENT OFFICE

2,447,480

COMBINED TABLE AND IRONING BOARD

Robert E. Stubbs, Duluth, Minn.

Application February 5, 1945, Serial No. 576,199

3 Claims. (Cl. 38—105)

1

This invention relates to household cabinets and has special reference to a combined table and ironing board unit.

The principal object thereof is that of providing exceptional convenience in storage capacity for instrumentalities commonly used in the art of ironing and general housekeeping.

Another object is to provide as substantial support as possible for the ironing board when in use as well as a like support and guide for the foldable leaves of the table top when in either of their adjusted positions.

Other objects and advantages of the invention may appear in the further comprehension and description thereof.

In the accompanying drawing forming part of this application wherein like reference numerals indicate like parts;

Fig. 1 is a perspective view of the cabinet in open position showing the ironing board folded therewithin and other of the cooperative parts of the assembly;

Fig. 2 is a transverse central sectional view of Fig. 1 partly in elevation;

Fig. 3 is a sectional view on the line 3—3, Fig. 2, and

Fig. 4 is a perspective view of one type of hinge for the union of the two parts of the ironing board.

In the drawing, the reference numeral 1 represents the major portion of the receptacle or box-like support of the unit, and the numeral 2 represents the lesser hinged cooperative part of the support which is fixed to the central portion 3 of the table top, the latter preferably being provided with the cooperative opposed hinged leaves 4—4 common to a kitchen or other table top.

One of the leaves occurring on that edge of the top which is free to be raised or lowered as desired by virtue of the hinges 5—5, has the double function of acting as a shelf for holding any object suitable for such holding when placed thereupon after such leaf has been turned down to horizontal position when the top is in open and vertical position.

At such time, the leaf will firmly rest upon the novel type of support which is slidably adjustable against the normally underface of the table top 3.

Each of these leaf rests is of a single rod-like metal piece having a U-shaped bight centrally thereof where doubled upon itself as at 6, thence turned at right angles at a distance preferably equal to the extent of said bight; thence passes through suitable openings in the wall 7 of the lesser part 2 of the box-like unit.

When thus in position against the under face of the top 3, the pair-like arms of each support are held reasonably tight against the top by means of a wooden block-like cleat 8 adjustably

2

carried by said top so that the supports may be held with any desired frictional tension against the top.

Thus it is apparent when the one for holding the uppermost leaf horizontally, as shown in dotted lines in Fig. 1, is in proper position for such service, the first right angle bend from the portion thereof forming the bight 6 will rest firmly upon the wall 7 of the lesser part 2 of the main housing of the unit forming an ideal dependable support for the leaf when in horizontal position.

Furthermore, it is to be noted that these bight-like supports by their peculiar permanent shape positively assure against the leaves at any time striking or bumping against the body of the unit when the top is either up or down.

The upper lesser section of the unit is, of course, provided with the usual secure foldable arm supports 9—9 for adjustably holding the parts together and which forms no part of the instant invention.

Within the upper part of the major portion 1 of the unit is normally stored the foldable ironing board comprising the sections 10 and 11, they being of such size and shape to thus occupy the principal area of such space.

Below the board when folded and permanently within the unit is the depending double lined safety well 12 for storing the sadiron whether hot or cold, and fixed upon the shelf-like section 13 of deck or floor installed level with the open top of the well 12 is the upright standard 14 for support of the sheet metal insulated hinged shelf 15 for intermittent temporary support of the sadiron while being used.

As a suitable adjustable support for the ironing board to permit of its being folded within the unit and also susceptible to unfolding and being raised upwardly and outwardly to the position on top of the front wall of the unit as shown in dotted lines in Fig. 2, there is provided the following:

Adjacent each of the opposite extremities of the sadiron well 12 is formed a vertically open channel 16 as by the pair of relatively wide but thin beams 17 fixed at both ends to the opposite walls of the unit.

Depending within and through each channel 16 is a wide, flat, oddly-shaped supporting leg 18 permanently fixed to the bottom section 10 of the ironing board, one adjacent each end thereof, such being to function as a positive strong support and guide for the board both while being moved to and from the interior of the unit and upon the upper edge of the front wall for ironing purposes.

These legs 18 are particularly odd in that each has an elongated narrow forwardly extending head portion 19 fixed securely to the underside of the section 10 of the ironing board and approach-

ing the full width thereof, the depending leg portion at its juncture with said head being in width materially less than one-half the length of said head and forming a notch therewith.

From thence downwardly, each leg widens considerably to form a substantial base connection with the shoe member 20 which is materially wider than the lower extremity of the leg to prevent any possibility of the latter passing completely upwardly through its respective channel and thus failing to function as intended.

As further strengthening and registering means, I provide two spaced, narrow stringers 21-21 and about the thickness of the board portion 10 and permanently attached to the bottom thereof so that the ends of the same where they occur at the hingedly united ends of the board sections extend materially therebeyond forming an ideal twin support and guide for the cooperative ends of the board when they are folded or unfolded.

While I have shown a simple type of flat metal hinge member as indicated at 22 being simply pivoted at each end within like opposed slots in the adjacent ends of the board, I have shown in Fig. 4 a modified form that might prove more desirable and efficient, the novel functioning of which will be described later.

A relatively short strong-back member 23 is fixed to the uppermost section 11 of the ironing board with one end projecting as at 24 and designed to function as an auxiliary cooperative support for the two sections when extended with their uppermost faces in the same plane as for example for ironing purposes.

It is to be seen that the upper edges of both pairs of beams 17 forming the channels 16 are notched as at 25 to receive the stringers 21-21 when the board is folded and within the unit as in Fig. 1 to further insure as stable a unit as possible when functioning as a table.

Another feature of the unit when open for use as an ironing instrumentality, is that of the automatically adjustable sadiron power supplying cord 26 which is shown as attached at one end to the iron 27 with its other end plugged into an outlet box 28 in the upper rearmost corner of the hinged section 2 of the unit and from where any desired length of intake cord 29 may terminate in a plug 30, such a length supposedly being convenient for storing within the unit.

The automatic feature of the feed line to the iron is accomplished by means of the trolley rod 31 diagonally disposed from the forward upper corner of the on-edge smaller section of the unit downwardly and rearwardly to adjacent the rearmost lower corner of said section where it remains in fixed position.

A weighted trolley 32 of any suitable shape having a suspending eye 33 attached thereto and threaded upon the trolley rod 31 will thus be free to travel in either direction on said rod but always biased by gravity to the lowermost end thereof.

From the lowermost extremity of this trolley 32 is suspend the flexible power cord 26 to the sadiron 27. This suspension comprises the clamp-like member 34 having a hole therethrough for accommodation of the cord 26, said hole being supplied with a resilient bushing 35 which, for example, may be rubber and will normally hold the cord 26 in any predetermined position but will permit the same to be drawn manually therethrough for any required length of cord.

From the outlet box 28, is run a suitable power

connection to any desired form of lamp 36 for illumination of the opened unit, the operation of said lamp may or may not be automatic.

It is to be noted that an auxiliary stabilizing support for the ironing board when in use is provided by the permanent installation of shelf 31 just above the opening for the door 38 in the front of the cabinet, said shelf being for the reception and support of the shoes 20 which are installed upon the two spaced legs 18 of the ironing board.

A modified assembly of hinge for the two portions 10 and 11 of the ironing board is shown in Fig. 4, and which may prove more efficient than that shown in the other views of the drawing, in that each hinge comprises a pair of housing portions 40-40, each having opposed laterally extending wings 41-41 for attachment to its respective board portion and pivotally carrying as at 42 within said housing portions 40, the opposite ends of the blade-like body member 43.

Having thus described my invention, what I claim and desire to secure by Letters Patent is:

1. A combined table and ironing board, including a base compartment section, parallel slots through the bottom of said base compartment section, a shelf attached to the forward wall of said section, and an ironing board having legs extendable through said slots so that said ironing board may rest upon the bottom of said section or be raised upwardly and forwardly into operative position with said legs resting upon said shelf.

2. A combined table and ironing board including a major base portion, a minor top portion, said portions being hinged along one pair of adjacent edges, a shelf attached to a wall of said base portion, slots through the bottom of said base portion and between opposite sides thereof, and an ironing board having legs extendable through said slots, so that said ironing board may rest within said base portion or be raised upwardly and forwardly into operative position with said legs resting on said shelf.

3. A combined table and ironing board including a major chambered base portion, a minor chambered top portion, an ironing board having spaced legs attached thereto, each leg having a notch therein, a shelf secured to the forward wall of said base portion, and slots through the bottom of said base portion spaced to receive said legs, whereby said ironing board may rest within said base portion or be raised to operative position with said legs resting upon said shelf and said notches engaging the upper edge of said forward wall.

ROBERT E. STUBBS.
